US0D1100452S

(12) **United States Design Patent** (10) **Patent No.:** **US D1,100,452 S**
(45) **Date of Patent:** **** Nov. 4, 2025**

(54) **SHOE UPPER**

(71) Applicant: **ON CLOUDS GMBH**, Zürich (CH)

(72) Inventors: **Olli Hirvonen**, Zürich (CH); **Dominic Schloegel**, Zürich (CH); **Timon Kuhlenkamp**, Zürich (CH)

(73) Assignee: **ON CLOUDS GMBH**, Zürich (CH)

(**) Term: **15 Years**

(21) Appl. No.: **29/886,844**

(22) Filed: **Mar. 14, 2023**

Related U.S. Application Data

(62) Division of application No. 35/513,789, filed on Feb. 10, 2022 (U.S. filing date under 35 U.S.C. 384), and having an international filing date of Feb. 10, 2022, now Pat. No. Des. 1,000,822.

(57) **CLAIM**

The ornamental design for a shoe upper, as shown and described.

DESCRIPTION

FIG. 1 is a perspective view of a shoe upper, showing the design;

FIG. 2 is a front view of the shoe upper, as shown in FIG. 1;

FIG. 3 is a rear view of the shoe upper, as shown in FIG. 1; FIG. 4 is a top view of the shoe upper, as shown in FIG. 1; FIG. 5 is a bottom view of the shoe upper, as shown in FIG. 1;

FIG. 6 is a side view of the shoe upper, as shown in FIG. 1; and,

FIG. 7 is a side view, opposite the side view shown in FIG. 6, of the shoe upper, as shown in FIG. 1.

The dashed lines are included for the purpose of showing environmental structure of the shoe sole that form no part of the claimed design.

1 Claim, 4 Drawing Sheets
